DESIGN FOR A CAN PUNCH

Harry L. Morris, Ocean View, Va.

Application November 10, 1947, Serial No. 142,413

Term of patent 3½ years

(Cl. D22—2)

To all whom it may concern:

Be it known that I, Harry L. Morris, a citizen of the United States of America, residing at Ocean View, in the county of Norfolk and State of Virginia, have invented a new, original, and ornamental Design for a Can Punch, of which the following is a specification, reference being had to the accompanying drawing, forming part thereof.

Figure 1 is a side elevational view of a can punch, showing my new design.

Fig. 2 is a plan view.

Fig. 3 is a front elevational view.

Fig. 4 is a rear elevational view.

Fig. 5 is a transverse sectional view through the handle, taken on line 5—5 of Fig. 3.

I claim:

The ornamental design for a can punch, as shown.

HARRY L. MORRIS.
